ICE AIR CONDITIONING SYSTEM

John M. Hall, New York, N. Y.

Application April 5, 1945, Serial No. 586,664

4 Claims. (Cl. 62—133)

1

This invention relates to new and useful improvements in an air conditioning system.

More particularly the new and improved air conditioning system is characterized by a box-like housing having an air inlet and an air discharge, and provided with a fan for circulating air through it. It is proposed to provide a support within said housing for a cake of ice so that an air stream blown through the housing by said fan will be cooled by the ice. This invention is particularly useful in bakeries where the heat is high, especially in the summer. However, it can be used in any place where the heat is unbearable.

The invention proposes a modified form in which an extension conduit is connected with the housing so that other rooms may also be cooled. A novel arrangement of baffle plates for guiding the air against the cake of ice, is also proposed.

Still further the invention proposes the construction of an air conditioning system, as briefly mentioned, which is exceptionally simple, contains no complicated machinery, which is desirable, and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an air conditioning system constructed in accordance with this invention.

Fig. 2 is a vertical sectional view taken on the line 2—2 of Fig. 1.

Fig. 3 is a fragmentary enlarged transverse vertical sectional view taken on the line 3—3 of Fig. 1.

Fig. 4 is a side elevational view of another air conditioning system constructed in accordance with a modified form of this invention.

Fig. 5 is a fragmentary enlarged horizontal sectional view taken on the line 5—5 of Fig. 4.

Fig. 6 is a fragmentary vertical sectional view taken on the line 6—6 of Fig. 5.

Fig. 7 is a fragmentary vertical sectional view taken on the line 7—7 of Fig. 5.

Fig. 8 is a fragmentary enlarged transverse vertical sectional view taken on the line 8—8 of Fig. 5.

Fig. 9 is a fragmentary enlarged sectional view taken on the line 9—9 of Fig. 8.

2

The new and improved air conditioning system, in accordance with this invention, includes a box-like housing 10 having an air inlet 11 and an air discharge 12. The housing 10 is substantially of L-shape in longitudinal vertical section. It is provided with a vertical portion 14 which connects with a horizontal portion 15. The vertical portion 14 is provided with a hollow top head 16 having louvered openings comprising said air inlet 11. An electric fan 17 is mounted in this head portion 16 and is capable of blowing air through the housing 10. The discharge 12 is in the nature of perforations and openings, in the top of the horizontal section 15.

A support 18 for a cake of ice 19 is arranged within the horizontal portion 15. This support 18 is of open work so that water from the ice may drain off. A drain pipe 20 is mounted in the bottom wall of the horizontal portion 15 and discharges into a tray 21 which is removably mounted in a space 22 formed in the bottom wall of the housing 10. The opening 22 is closed with a removable cover 23.

The electric fan 17 is provided with a starting rheostat 17^a for controlling the motor speed by a variable resistor. By means of this rheostat the air pressure may be increased or decreased by anyone.

The housing 10 is provided with a door built upon one side thereof. This door is normally held closed with a latch 26. When the door 25 is opened it is possible to reach the ice cake support 18 so that a cake of ice may be placed upon the support 18.

The operation of the air conditioning system may be understood from the following.

When the electric fan 17 operates it will blow a draft of air through the housing 10. The air will enter through the louvered air inlet 11. The stream of air will strike the cake of ice 19, and flow around the cake, and finally discharge through the air discharge 12. The discharged air will be cool, because the ice will absorb heat out of the air, in its passage through the housing 10.

In Figs. 4 to 9 inclusive, a modified form of the invention has been disclosed which is very similar to the prior form distinguishing in several ways. In this form of the invention the housing 10 is provided with an end extension conduit 28 which, in turn, is provided with an air discharge 29. Preferably this extension conduit 28 is connected with the end of the horizontal section 15 of the housing 10. The end of the housing is formed with additional perforations

12 or any other form of air discharge, so the air from the housing 10 may enter the extension conduit 28 and be discharged from the discharge 29. The extension conduit 28 may be extended to a different room or other quarters and may be attached to any part of the horizontal portion 15 of the housing 10, in Fig. 1 or Fig. 4.

The housing 10 is also provided with a group of baffle plates, and means for holding said plates in various positions so as to direct the stream of air against the ice cake in various ways. More specifically, there is a top pair of baffle plates 30, 31 and a similar bottom pair of baffle plates 30, 31. The baffle plates 30, 31 are connected with each other by hinge ears 32. The rear ends of the baffle plates 30 are formed with hooked portions similar to the hinge ears 32 which engage around support rods 34, which have their ends slidably engaged in horizontal slots 35 formed in the side walls of the housing 10. With this arrangement the rear ends of the baffle plates 30 are capable of sliding, and pivoting.

The front ends of the baffle plates 31 are formed with hooked portions 38 which are engaged about rods 39 supported upon racks 40. The racks 40 are slidably mounted through brackets 41 which are mounted on shafts 42. These shafts 42 are provided with gears 43 meshing with the racks 40. The shafts 42 are rotatively mounted upon the side walls of the housing 10, and project 30 through one of said side walls. The projecting ends of the shafts 40 are provided with arms 44 equipped with set screws 45, or other holding elements by which the arms 44 may be locked in various turned positions so as to lock the gears 35 43 correspondingly.

The hinges 32 of the baffle plates 30 and 31 are supported by cables 48 which are engaged over drums 49 mounted on shafts 50 rotatively supported across the side walls of the housing 10. One of the ends of each of the shafts 50 extends through one of the walls of the housing 10. These outer ends are provided with arms 51 equipped with clamping screws 46 by which they may be held in various turned positions.

The baffle plates 30 and 31 may be arranged to direct air against the cake of ice, in various ways. The hinge portions 32 of the baffle plates 30 and 31 may be moved towards each other, or away from each other so as to close the throat opening between the baffle plates 30. To do this, the arms 51 are freed, and then turned, so as to turn the shafts 50 and the drums 49 to let out, or draw in, the cables 48, as desired.

The front ends of the baffle plates 31 may be 55 moved towards each other, or away from each other, or may be raised, or lowered to various positions by freeing the arms 44 and turning said arms to turn the shafts 42 indirectly raise, or lower the racks 40 which in turn raise, or lower 60 the front ends of the baffle plates 31.

In other respects this form of the invention is identical to the prior form and like parts may be recognized by the same reference numerals.

The operation of the second form of the invention is identical to the first form except for the fact that the stream of air blown against the cake of ice may be controlled by controlling the baffle plates 30 and 31.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. An air conditioning system, comprising a box-like substantially L-shaped housing presenting connecting vertical and horizontal chambers, the vertical chamber being larger than said horizontal chamber and extending thereabove to provide an air intake column, an air inlet at the top of the vertical portion and an air discharge at the top of the horizontal portion, a fan in the top of said vertical portion for forcing air downwardly therethrough to circulate air through said housing, a support within said housing for a cake of ice, a door in said housing to make said support accessible, a drain beneath said support, a tray for said drain to discharge into, and baffle plates movably mounted in said housing for directing the air stream against said cake of ice.

2. An air conditioning system, comprising a box-like housing having an air inlet and an air discharge, a fan for circulating air through said housing, a support within said housing for a cake of ice, a door in said housing to make said support accessible, a drain beneath said support, a tray for said drain to discharge into, baffle plates movably mounted in said housing for directing the air stream against said cake of ice, and means for directing and moving said baffle plates, including means for raising and lowering the front ends of said baffle plates.

3. An air conditioning system, comprising a box-like housing having an air inlet and an air discharge, a fan for circulating air through said housing, a support within said housing for a cake of ice, a door in said housing to make said support accessible, a drain beneath said support, a tray for said drain to discharge into, baffle plates movably mounted in said housing for directing the air stream against said cake of ice, and means for directing and moving said baffle plates, including means for raising and lowering the front ends of said baffle plates, means for slidably and turnably supporting the rear ends of said baffle plates.

4. An air conditioning system, comprising a box-like housing having an air inlet and an air discharge, a fan for circulating air through said housing, a support within said housing for a cake of ice, a door in said housing to make said support accessible, a drain beneath said support, a tray for said drain to discharge into, baffle plates movably mounted in said housing for directing the air stream against said cake of ice, and means for directing and moving said baffle plates, including means for raising and lowering the front ends of said baffle plates, means for slidably and turnably supporting the rear ends of said baffle plates, and means for raising and lowering intermediate points along said baffle plates.

JOHN M. HALL.
